MINERAL SEPARATOR

John Broatch, Vancouver, British Columbia,
Canada

Application December 20, 1934, Serial No. 758,523

2 Claims. (Cl. 209—49)

My invention relates to improvements in mineral separators the objects of which are particularly to treat gold bearing black sands or pulps of low concentration in which float or flour gold or other precious metals are present. Further objects are to provide means for separating fine metallic particles from wet pulp, in which means no moving parts are required, and to provide a machine wherein copious amounts of pulp may 10 be dealt with.

The invention consists essentially of a curvilinear duct on the inner faces of the outer peripheries of which an adherent is to be applied and through which duct the pulp is adapted to flow, whereby the centrifugal force of the heavier particles of the pulp in their passage through the duct causes them to contact with the said adherent, as will be more fully described in the following specification and shown in the accompanying drawing, in which:—

Fig. 1 is a plan view of the invention.
Fig. 2 is a sectional view taken on the line 2—2 of Figure 1.

Fig. 3 is a plan view of a modified form of the invention providing for continuous mineral recovery.

In the drawing like characters of reference indicate corresponding parts in each figure.

The numeral 1 indicates a base having a circular step bearing 1A, upon which bearing a cylindrical drum 2 having an internal flange 2A is mounted. The drum is provided on its outer periphery with upper and lower flanges 3 and 4 and a spiral web 5 extending between said flanges 35 to define a spiral duct 6.

Communicating with the upper end of the duct 6 is a feed pipe 7 and communicating with the lower end is an outlet pipe 8.

Surrounding the drum 2 is a casing 9, which 40 is preferably made up of a plurality of curved plates 10 demountably held in position by pairs of bridges 11, which in turn are forced radially inwards by screws 12 mounted in standards 13. The plates 10 may be coated on their inner faces 45 with tar or any suitable adherent compound or may be used to hold similarly covered sheets of paper or fabric 14 in contact with the outer periphery of the flanges 3 and 4 and the spiral web 5 to render the duct 6 watertight and to 50 trap the precious metal.

In the modification shown in Figure 3, the upper flange 3 is extended and provided with a ring gear 15 which is engaged by a suitably driven worm shaft 16 and the drum 2 is rotatably journaled between a plurality of vertical rollers 17.

and is rotatably supported upon a step bearing 1A such as is shown in Figure 2. The inlet and outlet pipes 7 and 8 are brought to the centre of the drum as shown, so that the drum may be slowly rotated by the worm shaft 16 and pulp 5 run continuously through the inlet pipe 7, the duct 6 and the outlet pipe 8. A belt 18 which is coated with adhesive material as previously described is run between the rollers 17 and the drum, and is kept in firm contact with the spiral 10 web 5 by spring pressed plates 19 which extend between adjacent rollers 17.

In operating the device as shown in Figures 1 and 2, pulp is run through the inlet pipe 7, the duct 6 and the outlet pipe 8. In passing 15 through the duct its velocity sets up a centrifugal force which causes the precious metals to strike the adhesive coating on the paper 14 or the inner face of the plates 10 if the latter only are employed as a support for the adhesive. When 20 sufficient metallic mineral has been entrapped the plates are removed by slackening the screws 12 and the bridges 11, when the mineral deposit 25 can be removed by any desired means.

In the device as shown in Figure 3, the worm 25 shaft 16 is driven to slowly rotate the drum 2 and feed around the duct 6 the belt 18 with its coated side in contact with the web 5. The drum would be rotated at such slow speed that the belt having made one complete turn with the drum, 30 would be so coated with metallic particles as to need cleaning, so that as the belt passes outwards from the drum the tar coating and its metallic mineral content are removed by any suitable means and the metallic mineral recovered. An amalgamating substance may obviously 35 be substituted for the tarry adhesive above referred to.

The action relied upon is to pass a stream of pulp around a series of curves or a continuous 40 curve at such speed as will by virtue of the pulp flow alone around said curve or curves, set up centrifugal force in the stream to throw the metallic mineral into contact with an outer peripheral surface to trap it, consequently it will 45 be apparent that the invention will not be limited, except as expressed in the claims, to the structures particularly shown herein.

What I claim as my invention is:

1. A metallic mineral recovery device comprising 50 a drum having on its outer periphery a spiral duct having an inlet and an outlet, an outer cover for the drum, said cover being adapted to support a belt coated with a metallic particle entrapping substance at the outer periphery 55

of the duct, means for rotating the drum within the cover, and means for continuously feeding the belt between the cover and the drum.

2. A metallic mineral recovery device comprising a rotatable cylindrical body having on its outer periphery a spiral groove, an inlet and an outlet to the groove in alignment with its vertical

axis, a plurality of rollers mounted on vertical axes about the body, a belt adapted to be passed about the body and held in contact therewith by said rollers, and plates interposed between adjacent rollers adapted to urge the belt into intimate contact with the cylindrical body. 5

JOHN BROATCH.
